ABSTRACT: The supply of liquid fuel to a burner, for example in a glass melting tank, is controlled by apparatus including a shutoff valve in a fuel supply line, and a sealed chamber communicating with the supply line between the shutoff valve and the burner, which chamber has a flexible wall portion which enables the volume of the chamber to be varied when the shutoff valve is operated.

BURNER CONTROL

BACKGROUND OF THE INVENTION

1. Field of the Invention

This invention relates to apparatus for controlling the supply of liquid fuel to burners and, more especially, to apparatus for controlling high pressure liquid fuel supply to burners in industrial heat treatment processes.

2. Description of the Prior Art

Liquid fuel burners are used extensively in industrial heat treatment processes. In, for example, the firing of continuous glass melting tanks two banks of oil burners are located in opposite sidewalls of the glass tank and the burner banks are operated alternately so that all the burners at one side of the tank are activated for a period of about 20 minutes and are then extinguished and then all the burners on the other side of the tank are activated for a 20 minute period.

A serious difficulty exists when the fuel supply to a burner is discontinued by closing a shutoff valve in a fuel supply line to the burner, since the fuel in the supply line between the shutoff valve and the burner will continue to flow through the burner after the shutoff valve is closed, particularly if the fuel supply pressure is high. This is not detrimental to the operation of the process whilst atomizing air is maintained at full power and combustion air is also being supplied to the burner. However, this fuel will in general leak from burner after the supply of combustion air to the burner has been discontinued and consequently the leaking fuel burns with incomplete combustion, generating smoke. This is particularly undesirable where a glass tank is being fired as the interior of the tank can be clouded, adversely affecting material undergoing treatment in the tank.

To overcome this serious problem it is known to provide an expandable chamber in communication with the fuel supply line between the shutoff valve and the burner. Such known expandable chambers comprise a cylinder having a piston slidably mounted therein, the piston being arranged to be displaced, when the shutoff valve is closed, in a sense to expand the volume of the cylinder in communication with the fuel supply line and thereby cause a rapid reduction in the fuel pressure in the supply line. Fuel is therefore sucked through the supply line away from the burner, and leakage of fuel through the burner is avoided.

Such expandable volumes are effective in preventing fuel leakage after a burner has been shut off, but it is difficult to provide an adequate and lasting seal between the piston and its cylinder, particularly where the fuel supply pressure and temperature are relatively high.

An object of the present invention is to provide apparatus for controlling the supply of liquid fuel to a burner which is effective to prevent fuel leakage when the burner fuel supply is shut off and which is devoid of moving seals.

SUMMARY

According to the present invention apparatus for controlling the supply of liquid fuel to a burner, comprises a fuel supply line containing a shutoff valve, a sealed chamber communicating with the supply line between the shutoff valve and the burner, a flexible wall portion in said chamber, and control means operatively connected with the shutoff valve and adapted to move said wall portion in a sense to increase automatically the volume of the chamber in communication with the supply line when the shutoff valve is closed.

Preferably the control means are further operable to move the wall portion automatically in a sense to decrease the volume of the chamber in communication with the supply line when the shutoff valve is opened.

In a preferred embodiment of the invention the flexible wall portion comprises a first flexible diaphragm which divides a diaphragm vessel into two chambers, which diaphragm is mechanically connected to a second diaphragm which divides a second vessel into two chambers, one of the chambers defined by said first diaphragm communicates with the fuel

supply line, and the control means includes pressure fluid lines connected to the other three chambers defined by the diaphragms, and valve means connected to said pressure fluid lines and selectively operable to supply pressure fluid controlling the movement of the diaphragms and hence the volume of the chamber communicating with the fuel supply line.

In another embodiment of the invention the flexible wall portion comprises a collapsible bellows disposed in the chamber, the interior of the bellows being sealed from that part of the chamber which is in communication with the fuel supply line, the control means controlling the pressure of fluid in a pressure fluid line communicating with the interior of the bellows to control the expansion of the bellows and thereby the volume displaced by the bellows in said part of the chamber. When the shutoff valve is closed, the control means cause the bellows to contract, increasing the volume of the chamber in communication with the fuel supply line, so that fuel is sucked from the supply line away from the burner and leakage of fuel is prevented. When the shutoff valve is opened to permit the flow of fuel to the burner the control means cause the bellows to expand to reduce the volume of the chamber in communication with the supply line, and thus to prepare the chamber for the next shutoff operation.

In another embodiment of the invention the sealed chamber is constituted by the interior of a collapsible bellows, the control means controlling the pressure of fluid in a pressure fluid line communicating with an enclosure surrounding said bellows so as to control the expansion and contraction of the bellows and thereby the volume of the sealed chamber. When the shutoff valve is closed, the control means cause the bellows to expand, and when the shutoff valve is opened the control means cause the bellows to contract.

Preferably expansion and contraction of the bellows is assisted by an actuator rod connected to one end of the bellows. The actuator rod may be movable by means of a double-acting fluid-pressure operated piston, extension and retraction of which is controlled by said control means.

The control means preferably include a control valve operatively connected to the shutoff valve so that when the shutoff valve is open the control valve is disposed in a first setting in which it connects a pressure fluid source to said pressure fluid line so as to reduce the volume of the chamber communicating with the fuel supply line and when the shutoff valve is closed the control valve is disposed in a second setting in which it connects an exhaust outlet with the said pressure fluid line to cause an increase in the volume of said chamber in communication with said supply line.

In the said one embodiment the said pressure fluid line also communicates with the side of said piston remote from the bellows, said pressure fluid line being connected selectively to the pressure fluid source or to the exhaust outlet according as the control valve is disposed in said first or said second setting respectively.

60 A common actuator may be provided for operating both the control valve and the shutoff valve. Preferably the control valve is operable by the actuator through a lost motion connection such that the control valve is moved from its first into its second setting only when the shutoff valve is fully closed or substantially fully closed.

In one embodiment the control valve comprises a spool valve having a linearly displaceable valve member and the lost motion connection comprises a tappet arm attached to an actuator and engaging the valve member only when the actuator approaches its position corresponding to the shutoff valve being fully closed.

The invention also includes a liquid fuel burner provided with apparatus as hereinabove defined for controlling the supply of fuel thereto. —

BRIEF DESCRIPTION OF THE DRAWINGS

FIG. 1 is a purely diagrammatic partial section through a burner fitted in a glass melting tank, and provided with apparatus according to the invention, for controlling the supply of liquid fuel to the burner, indicated schematically,

FIG. 2 shows diagrammatically the apparatus, partially in section, for controlling the fuel to the burner shown in FIG. 1, and

FIG. 3 is a section through a two-diaphragm device which constitutes a modification of the apparatus of FIGS. 1 and 2.

DESCRIPTION OF THE PREFERRED EMBODIMENT

Referring to FIG. 1 a burner B is supplied with fuel oil by way of a fuel supply line 11, and with atomizing air by way of an air supply line 12. The burner B is disposed centrally in the outlet of a combustion air duct 13 which enters a side wall of a glass melting tank.

A shutoff valve 14 is included in the fuel supply line 11. The valve 14 has an actuating lever 15 (FIG. 2) which is slotted at 16 to receive a sliding pin 17 provided at one end of a piston rod 18. The piston rod 18 is connected to a piston 19 slidably mounted in a cylinder 20, so that the opening and closing of the shutoff valve 14 is dependent upon the position of the piston 19 within cylinder 20. Thus retraction of the piston 19 towards the right-hand end of the cylinder 20, as shown in full lines in FIG. 2, closes the valve 14 and extension of the piston 19 towards the left-hand end of the cylinder 20, as shown in broken lines, opens the valve 14, permitting the supply of oil through the supply line 11 to the burner B.

The cylinder 20 has two fluid supply lines 21 and 22 connected thereto, the line 21 communicating with the smaller area side of the piston 19 and the line 22 communicating with the larger area side of the piston 19. The fluid pressure lines 21 and 22 enter the cylinder 20 in the unswept end volumes thereof. Respective three-way valves 21a and 22a in the lines 21 and 22 respectively have two respective positions in which they connect the respective lines 21 and 22 with a common fluid pressure source P or with atmosphere respectively.

The piston rod 18 carries a tappet arm 23 which, in the extreme retracted position of the piston 19 (shown in full lines) corresponding to closure of the valve 14, engages operatively one end of a spool valve member 24, moving the latter slidably in a five-port valve housing 25 against the action of a thrust spring 25' engaging the other end of the spool valve member 24.

The spool valve member 24, and the ports in the housing 25, are so arranged that, when the valve member 24 is moved by the arm 23 towards the right-hand end of the housing 25, a fluid pressure line 26 extending from the source P is connected to a line 27, while a line 28 is connected to an exhaust outlet 29. When the spool valve member 24 is released the spring 25' urges the member 24 towards the left-hand end of the housing 25, connecting the line 26 to the line 28 and connecting the line 27 to an exhaust outlet 30.

The line 28 is branched into two branch lines 28a, 28b. The branch line 28a passes through a plate 31 which forms the base of a closed chamber 32, the branch line 28a communicating with the interior of a bellows 33 secured at its lower end to the base plate 31. At its upper end the bellows 33 carries a plate 34 which is connected to a piston rod 35. The piston rod 35 passes downwardly through a fluid seal 36 in base plate 31 and is connected to a piston 37 which is slidably mounted in cylinder 38 attached to the under surface of the plate 31. The branch line 28b opens into the cylinder 38 beneath the piston 37 that is, on the larger area side thereof, so that the cylinder volume beneath the piston 37 and the interior of the bellows 33 are always at the same pressure, that is, the pressure within the line 28.

The line 27 opens into the cylinder 38 in the unswept volume thereof above the piston 37 (that is on the smaller area side of the piston 37). A line 39 connects the interior of the chamber 32 externally of the bellows 33 with the supply line 11 between the burner B and the shutoff valve 14.

The operation of the apparatus will now be described.

To operate the burner B combustion air is first supplied to the combustion region at a rate of about 500 cu. ft. per minute through the duct 13, and atomizing air is then supplied to the burner B at a pressure in the region of 80 p.s.i. through the supply line 12. The shutoff valve 14 is then opened to admit fuel oil at a pressure of 60 p.s.i. to the burner B through the supply line 11, the rate of flow of atomizing air to the burner B being about 80 cu. ft. per minute.

- 10 The valve 14 is moved into and maintained in the open position by connecting the line 21 to exhaust and the line 22 to the pressure source P, extending the piston 19 into and retaining it in its position at the left of the cylinder 20 as shown in FIG. 1 in broken lines. The tappet arm 23 is out of contact with the spool valve member 24, which is urged towards the left-hand end of the housing 25 by the spring 25' to connect the line 27 to the exhaust outlet 30 and the line 28 to the fluid pressure line 26. Pressure fluid is supplied to the larger area side of the piston 37 by way of the branch line 28b and to the interior of the bellows 33 by the branch line 28a, and the combined upward fluid pressure extended on the piston 37 and the plate 34 of the bellows 33 causes the bellows 33 to rapidly expand. The volume of the chamber 32 communicating with the supply line 11 is therefore reduced to its minimum value.
- 15 To terminate operation of the burner B the settings of the valves 21a and 22a are reversed so that the line 22 is connected to exhaust and pressure fluid is supplied from the source P by way of the line 21 to the left-hand side of the piston 19, thereby causing the latter to retract to the right to the position illustrated in FIG. 1 in full lines. This retraction of the piston 19 is transmitted through piston rod 18, the pin 17, and actuating member to the valve 14, closing the latter and terminating the supply of fuel oil along the supply line 11 to the burner B.
- 20 Near the end of the retracting movement of the piston 19 the tappet arm 23 engages and depresses the spool valve member 24 against the action of the spring 25' moving the spool valve member 24 to the right-hand end of the housing 25. The line 27 is thereby connected to the pressure source P through the fluid pressure line 26 and the line 28 is connected to the exhaust outlet 29. The interior of the bellows 33 and the larger area side of the piston 37 are connected to exhaust (i.e. to atmosphere) whilst fluid under pressure is supplied to the cylinder 38 on the smaller area side of the piston 37; this causes the bellows 33 to contract rapidly, reducing the pressure in the chamber 32 and increasing rapidly the volume of the chamber 32 in communication with the supply line 11, oil remaining in the line 11 is therefore sucked into the chamber 32, said oil flowing back along that part of the supply line 11 between the line 39 and the burner B. Leakage of oil from the burner B after closure of the valve 14 is thereby eliminated.
- 25 The bellows 33 provide a rapid and effective means for increasing the volume of the chamber 32 in communication with the supply line 11, without the necessity of sliding seals in the oil filled chamber 32. The use of a flexible or collapsible wall portion, such as the bellows 33, therefore gives the apparatus a longer effective service life than is obtainable with piston and similar devices requiring sliding seals.
- 30 It will be appreciated that the present invention has been described by way of example only with reference to a specific embodiment and that many variations and modifications of the invention will be apparent to persons skilled in the art. Thus whilst the control means for the bellows 33 has been described as a fluid pressure system it will be apparent that other control systems, such, for example, as hydraulic or pneumatic systems, can be used. For example, the cylinder 20 can be supplied with hydraulic pressure, whilst the bellows 33 and the cylinder 38 can be pneumatically operated.
- 35 In an alternative embodiment of the invention, for example, the arrangement of the bellows 33 in the chamber 32 could be modified so that the interior of the bellows 33 communicated with the supply line 11 through the line 39 and was, therefore, filled with oil. The chamber 32 surrounding the bellows 33 would then communicate with line 28a, expansion and con-

traction of the bellows 33 being controlled as described above. In a further alternative the bellows 33 could be replaced by, for example, a flexible diaphragm device.

A modification of the apparatus of FIGS. 1 and 2 is illustrated in FIG. 3. Two identical diaphragm vessels 40 and 41 are secured to opposite ends of a frame 42. The vessel 40 comprises two cup shaped halves 43 and 44 with a flexible diaphragm of an oil-resistant rubber peripherally clamped between the two halves 43 and 44. A central bearing 46 integral with half 44 forms the bearing for a diaphragm actuating rod 47 whose upper end 48 is sealed into the center of the diaphragm. The lower end 49 of the bearing 46 is reduced and screw cut, and this reduced end 49 is fitted downwardly into a hole in the upper part of the frame 43 and is secured by a nut 50.

The second diaphragm vessel 41 is identical with vessel 40 and comprises halves 51 and 52 between which a second flexible diaphragm 53 is peripherally clamped. The upper half 52 has a central integral bearing 54 which is held in the lower part of the frame by a nut 55. A diaphragm actuating rod 56 is slidably supported in boring the bearing 54, and the lower end of the rod 56 is sealed at 57 into the center of the diaphragm 53.

The diaphragm actuating rods 47 and 56 are in axial alignment with each other towards one another within the frame 42. The lower end of the rod 47 is screw cut with a left-hand thread, and the upper end of the rod 18 is screw cut with a right-hand thread and the threaded ends of rods are connected by a turn buckle 58 so that the diaphragms 45 and 53 are mechanically connected for mutual displacement.

The upper sealed chamber of vessel 40 i.e. the chamber between the half 43 and the diaphragm 45 is connected by a line 59 to the fuel supply line 11, and the lower chamber of vessel 40, i.e. the chamber between the half 44 and the diaphragm 45 is connected to the branch line 28a. The upper chamber of a vessel 41, i.e. the chamber between the half 52 and the diaphragm 53, is connected to line 27, and the lower chamber of vessel 41 i.e. between the half 51 and the diaphragm 53 is connected to the branch line 28b.

Branch lines 28a and 28b are connected to pressure line 28 as in FIG. 2 which extends to the five port valve, and pressure line 27, also extends to the five port valve of the control system.

With the burner firing, air under pressure is supplied through the five port valve to the line 28 and from the line 28 the branches 28a and 28b so that the lower chambers of vessels 40 and 41 are connected to a high-pressure air source (about 60 p.s.i.), while the upper chamber in vessel 41 is connected through line 27 to exhaust. The upper chamber of vessel 40 is open to the fuel line 11; and in this position both diaphragms 45 and 53 are raised so that the upper chamber of vessel 40 has a minimum volume.

When the burner stops firing and the shutoff valve 15 is closed to operate the five port valve, the line 28 is connected to exhaust so that through branch lines 28a and 28b the lower chambers of both vessels 40 and 41 are connected to exhaust, and air under pressure is supplied by line 27 to the upper chamber of vessel 41. Because the shutoff valve is closed the oil pressure in the chamber of vessel 40 is substantially at atmospheric pressure. The pressure of air in the upper chamber of vessel 41 causes downward displacement of diaphragm 53 which, through the rod 56, the turn buckle 58 and the rod 15, causes a simultaneous downward displacement of the diaphragm 45 which increases to a maximum the volume of the upper chamber of vessel 40. This causes any fuel oil in the line 11 to be drawn into that sealed chamber.

Both the diaphragms 45 and 53 are made from a rubber which is capable of withstanding the high temperature, high pressure oil.

The burner control apparatus of the invention finds particular application in the control of banks of oil burners disposed in opposite sidewalls of a continuous glass melting tank. The banks of burners are operated alternately for periods of about 20 minutes each.

When the burners of one bank are being operated the combustion exhaust gases are drawn off from the tank down the combustion air supply ducts of the inactive burners and these hot gases are passed through heat-retaining means, such as stacks of brickwork, which absorb heat from the exhaust gases passing therethrough and thus when the burner cycle is reversed and the opposite bank of burners is operated and combustion air is drawn in through the said combustion air supply ducts, said combustion air is preheated by passage through the heated heat-retaining means.

When the operation of a liquid fuel burner or a said bank of burners is to be terminated the following operations are effected in sequence:

1. The fuel supply to the burners is discontinued by closing a shutoff valve in a fuel supply line connected to the burners;

2. The supply of "atomising" air to the burners, is reduced to about 25 percent of its fully operational value; and,

3. The "combustion" air supply is terminated.

20 When the burners of one bank are inactive they lie in the path of the exhaust gases from the active bank of burners and a supply of atomizing air, at a reduced pressure, is maintained to the inactive burners to serve as a coolant and to prevent blocking of the inactive burners by foreign matter or soot carried in the exhaust gases from the active burners.

When the burners of the inactive bank of burners are to be reactivated the supply of combustion air is first reinstated, then the supply of atomizing air is increased to its full pressure and finally the shutoff valve in the fuel supply line to the burners are opened.

I claim:

1. Apparatus for controlling the supply of liquid fuel to a burner, said apparatus comprising a fuel supply line containing a shutoff valve, a sealed chamber communicating with the supply line between the shutoff valve and the burner, a flexible wall portion in said chamber, motive means operable selectively to move said wall portion in a sense to increase the volume of said chamber and in the opposite sense to decrease the volume of said chamber, and control means for said motive means operative responsively to closing and opening of the shutoff valve, said control means automatically causing said motive means to move said wall portion in the sense to increase the volume of said chamber when the shutoff valve is closed and in said opposite sense to decrease the volume of said chamber when the shutoff valve is opened.

2. Apparatus as claimed in claim 1, wherein the flexible wall portion comprises a first flexible diaphragm which divides a diaphragm vessel into two chambers one of which chambers comprising the sealed chamber which communicates with the fuel supply line, the motive means comprise a mechanical connection between said first diaphragm and a second diaphragm which divides a second vessel into two chambers, and means to supply pressure fluid in pressure fluid lines connected to the other three chambers defined by the diaphragms, and the control means comprise valve means connected to said pressure fluid lines and selectively operable to supply pressure fluid controlling the movement of the diaphragm and hence the volume of the sealed chamber.

3. Apparatus according to claim 2, in which said control means includes a control valve operatively connected to the shutoff valve so that when the shutoff valve is open the control valve is disposed in a first setting in which it connects a pressure fluid source to said pressure fluid line so as to reduce the volume of the chamber communicating with the fuel supply line and when the shutoff valve is closed the control valve is disposed in a second setting in which it connects an exhaust outlet with the said pressure fluid line to cause an increase in the volume of said chamber in communication with said supply line.

4. Apparatus according to claim 3, in which a common actuator is provided for operating both the control valve and the shutoff valve.

5. Apparatus according to claim 4, in which the control valve is operable by the actuator through a lost motion con-

nection such that the control valve is moved from its first into its second setting only when the shutoff valve is fully closed or substantially fully closed.

6. Apparatus according to claim 5, in which the control valve comprises a spool valve having a linearly displaceable valve member and the lost motion connection comprises a tappet arm attached to the actuator and engaging the valve member only when the actuator approaches its position corresponding to the shutoff valve being fully closed.

7. Apparatus according to claim 1, in which the flexible wall portion comprises a collapsible bellows disposed in the chamber, the interior of the bellows being sealed from that part of the chamber which is in communication with the fuel supply line, the motive means comprise means to supply pressure fluid in a pressure fluid line communicating with the interior of the bellows, and the control means comprise valve means connected to said pressure fluid line and selectively operable to supply pressure fluid controlling the expansion and contraction of the bellows and thereby the volume displaced by the bellows in said part of the chamber.

8. Apparatus according to claim 7, in which expansion and contraction of the bellows is assisted by an actuator rod connected to one end of the bellows.

9. Apparatus as claimed in claim 1, in which the sealed chamber is constituted by the interior of a collapsible bellows, the motive means comprise means to supply pressure fluid in a pressure fluid line communicating with an enclosure surrounding said bellows, and the control means comprise valve means connected to said pressure fluid line and selectively operable to supply pressure fluid controlling the expansion and contraction of the bellows and thereby the volume of the sealed chamber.

10. Apparatus according to claim 9, in which expansion and

contraction of the bellows is assisted by an actuator rod connected to one end of the bellows.

11. Apparatus according to claim 10, in which the actuator rod is movable by means of a double-acting fluid-pressure operated piston, extension and retraction of which is controlled by said control means.

12. Apparatus according to claim 11, in which the said pressure fluid line also communicates with the side of said piston remote from the bellows, and valve means associated with said pressure fluid line is operable to connect said line selectively to a pressure fluid source or to an exhaust outlet.

13. A liquid fuel burner provided with control apparatus according to claim 1.

14. Apparatus according to claim 1, wherein said motive means comprise fluid pressure means to cause movement of said flexible wall portion in both senses, and said control means comprise valve means whose setting controls the fluid pressure means of said motive means and is changed responsive to closing and opening of said shutoff valve.

15. Apparatus according to claim 1, wherein said motive means comprise an actuator rod connected to a surface of said flexible wall portion of said sealed chamber which surface is an external surface with respect to said sealed chamber, and a double-acting fluid-pressure operated piston for moving the actuator rod and thereby the flexible wall portion in both senses, extension and retraction of the piston being controlled by said control means.

16. Apparatus according to claim 15, wherein said control means comprise valve means whose setting controls the pressure of fluid delivered to said piston and is changed responsive to closing and opening of said shut-off valve.
